THE NORRIS PETERS CO., PHOTO-LITHO., WASHINGTON, D. C.

UNITED STATES PATENT OFFICE.

WILLIAM McDUGAL HENRY, OF KESLEY, IOWA.

ENVELOP-SEALER.

SPECIFICATION forming part of Letters Patent No. 738,610, dated September 8, 1903.

Application filed September 27, 1902. Serial No. 125,087. (No model.)

To all whom it may concern:

Be it known that I, WILLIAM McDUGAL HENRY, a citizen of the United States, and a resident of Kesley, in the county of Butler 5 and State of Iowa, have invented new and useful Improvements in Envelop- Sealers, of which the following is a full, clear, and exact description.

This invention relates to improvements in sealing devices for envelopes, particularly envelopes for expressing money or other valuables, the object being to provide a simple device for this purpose that may be quickly sealed and the use of wax and tape or ribbon 15 be dispensed with.

I will describe an envelop-sealer embodying my invention and then point out the novel features in the appended claims.

Reference is to be had to the accompanying 20 drawings, forming a part of this specification, in which similar characters of reference indicate corresponding parts in all the figures.

Figure 1 is a back view of an envelop, showing sealing devices embodying my invention 25 as applied thereto. Fig. 2 is a section on the line 2 2 of Fig. 1. Fig. 3 is a section on the line 3 3 of Fig. 1. Fig. 4 is a section showing a modification.

Referring first to the envelop shown in 30 Figs. 1 and 2, 10 designates the front of the envelop, 11 the back, and 12 the flap on the upper edge of the front adapted to fold over upon the back. Overlapping flaps 13 and 14 extend from the ends of the front end and 35 engage upon the back of the envelop. As an additional safety I provide an auxiliary or inner flap 15, which is secured to the inner side of the front of the envelop and folds upon the overlapping portion 14. Instead of 40 using mucilage or other adhesive for securing the parts I preferably employ metal fastening devices 16, which are here shown in the form of ordinary paper-clips; but it is to be understood in practice that I will employ 45 small light rivets.

I have shown three main sealing devices in connection with the envelop, each consisting of a metal disk 17, engaging on the outer side of the envelop-flap 12 and having extended 50 from its edge at suitable distances apart metal fingers 18, which are provided at the edge with eyes 19, and the body portions of

the fingers are engaged against the inner surface of the disk 17, and then the ends are turned outward to form fastening-prongs 20. 55 These fastening-prongs 20 are passed through the flap, as clearly shown in Fig. 2, and the eyes 19 are also passed through the flap, and then a wire ring 21 is passed through the several eyes. This will effectually hold the 60 disk in position, and it cannot be removed without mutilating the flap.

Coacting with the fastening member just described is the inner fastening member, consisting of a concave disk 22, secured to the 65 inner sides of the overlapped portions 13 and 14. As a means for fastening this inner disk, or, as it may be termed, a "clenching-disk," it is provided at its edge with fingers 23, designed to be passed through the portions 13 70 and 14 and turned down against the portion 14.

In sealing the envelop the flap 12 is to be turned down and the prongs 20 forced through the material, and when the ends engage with the concave disk 22 the prongs will be turned 75 outward. A suitable machine may be provided for this purpose. If the prongs are sufficiently light and flexible, however, the parts may be pressed by a person's fingers. 80

The inner or auxiliary flap 15 is provided with a sealing device consisting of a disk 24, attached by means of prongs or fingers to the flap and having portions or fingers 25 turned inward and provided with prongs, as in the 85 fastener first described, and these prongs are turned outward by means of a concave plate 26, secured to the inner side of the back of the envelop.

In Fig. 4 the fastening device is similar to 90 that first described; but the envelop has an auxiliary flap portion 27 extended from the upper edge of its back and designed to turn into the envelop.

Having thus described my invention, I 95 claim as new and desire to secure by Letters Patent—

1. An envelop-sealer comprising a disk attached to the flap of the envelop and having prongs, a fastening-wire engaging with the 100 disk and with the envelop and a clenching-disk secured to the envelop, the said clenching-disk being concaved to force the prongs outward when pressed against the same.

2. An envelop-sealer comprising a disk, portions extended from the edge of said disk inward and then outward to form prongs, eyes being formed in said portions at the edge of the disk, a wire passed through said eyes and engaging against the inner side of the envelop-flap, while the disk engages the outer side thereof, and a clenching-disk secured to the back portion of the envelop.
10. 3. An envelop-sealer comprising a disk for engaging against the outer side of the envelop-flap, portions extended from the edge of said disk against the inner surface of the disk and having the end turned outward to form prongs, eyes formed at the edge of the disk, a wire passing through said eyes and engaging against the inner side of the flap, a con-
- 15

caved disk, and fingers on the edge of said disk for securing the same to the envelop.

4. An envelop comprising a front or body, overlapping flaps extending from the ends of the front and engaging on the back, a main flap on the upper edge of the front, an auxiliary flap secured to the inner side of the front and folding over the overlapping flap, independent metallic sealing devices for the main and auxiliary flaps.

In testimony whereof I have signed my name to this specification in the presence of two subscribing witnesses.

WILLIAM McDUGAL HENRY.
